UNITED STATES PATENT OFFICE.

JOSEPH R. DUMONT, OF KANSAS CITY, MISSOURI, ASSIGNOR TO MAUDE FRANCES DUMONT, OF KANSAS CITY, MISSOURI.

DIRECTORY RACK.

Application filed October 23, 1924. Serial No. 745,368.

This invention relates to directory racks, especially designed for temporarily receiving cards and the like upon which is placed certain indicia.

5 The invention is particularly applicable for use as a hotel rack in which guest cards may be contained and which may be removably attached to the rack in a convenient and expeditious manner, although it is equally 10 applicable for use as a rack for supporting information cards for general business wherever credit cards, customers' list or other indicia-containing cards are used.

The invention is primarily an improvement 15 on my Patent No. 1,444,240, granted February 6, 1923, but the card supporting bars may be used with other racks if desired. The present invention relates to the card bar per se and the card bar in combination 20 with the rack. In my former patent, card bars were employed which very closely resembled the construction of card bar shown in this application but with the card bars in the patented construction, the cards did not 25 lie flat one upon the other but extended out at angles to the card rack, whereas, with my present invention, the cards do lie flat approaching more nearly a vertical plane so the appearance of the rack as a whole when 30 the cards are in it, is improved and the data is more easily read. Then too, with my present invention, I employ a flexible card bar which may be inserted into the rack by 35 springing the middle portion or bowing it so that the distance in a straight line between the two ends will be reduced, the flexible bar having enough resiliency or spring to it to allow it to spring back into place in the 40 rack when the pressure on the metal box is relieved and offset hooks on the card bar assist in allowing the cards to lie flat.

The novel construction and advantages of 45 my invention will be apparent by reference to the following description in connection with the accompanying drawings, in which—

Fig. 1 is a perspective view of a rack constructed in accordance with my invention, parts being broken away to better illustrate 50 other parts.

Fig. 2 is a longitudinal sectional view through part of the rack.

Fig. 3 is a detailed perspective view of one 55 of the card supporting bars.

Fig. 4 is a like view of the card supporting

bar opposite to that shown in Fig. 3, and Fig. 5 is a top edge view of the card supporting bar, the dotted line position of the end showing how the bar is shortened by bending it in the middle.

60 The rack frame is shown as consisting of a back plate 1 having channel side rails 2 and 3, a top rail 4 and a bottom rail 5. Secured to the top rail 4 is a bowed spring 6 secured intermediate its ends and adapted to bear 65 upon the top card bar as will be clearly apparent by reference to Fig. 1, said top bar being partly broken away in Fig. 1.

The card bars are shown as comprising 70 channels 7 having portions of their tops cut away to provide the end fingers 8 and 9 and the intermediate card receiving fingers 10. The card receiving fingers are offset with respect to the web portion 11 of each bar and the bottom flange 12 of the channel is cut 75 away intermediate its ends as for example 13 and 14, the cut-away portions 13 and 14 corresponding with portions 15 and 16 in the top edge of the channel so that the bar 7 may be flexed or bent intermediate its ends. 80

The offset hook-shaped members 10 are 85 adapted to pass through openings 17 in the cards 18 so the cards will hang from the offset hook portions away from the main body portion of the bars and therefore they will be permitted to lie flat one upon the other. The bottom bar may rest upon the slide 19 supported by the hinged plate 20 and the hooking bars rest one upon the other, the top bar being held down by the spring 6. 90

When it is desired to take out a bar, it may be grasped as shown in Fig. 1, the middle portion being bent or flexed so that the ends 8 and 9 may be sprung out of engagement with the channel side rails 2 and 3, then the old card can be removed and a new card can be hung on the offset hooks 10. The inwardly extending ends 8 and 9 which are part of the upper channel before it is cut away and the bottom flange 12 are 100 of the same widths, each being slightly less than the widths of the channels 2 and 3 so that the bars can freely slide in the frame and when the bars are put in place, they rest one upon the other as shown.

105 It will be seen from the foregoing that the bars can readily be applied to and removed from the rack and that they can be conveniently flexed so that they can be removed from the frame without disturbing 110

any of the other bars and that inasmuch as the hooked portions are offset, the cards, where they are supported by the bars will stand out from the webs 11 of the bars so 5 they can swing down flat against the cards beneath them. This improves the appearance of the rack and enables the cards to be more readily inspected.

It will also be apparent that the flanges 10 9 and 12 are about equal to the depths of the grooves while the offset hooks have their free edges spaced from the back plate so that the hooks do not extend to the rear edges of the flanges 9 and 12. Therefore 15 while the flanges fill the grooves in which they slide, the hooks are spaced a sufficient distance from the rear panel to permit the cards to be put in place and removed while the card bars are in the rack.

20 What I claim and desire to secure by Letters-Patent is:—

1. A device of the class described comprising a frame having grooved side guides and a back, transverse card carrying bars, 25 each having ends engaging the guides and provided along its bottom edge with a horizontal flange, rearwardly projecting offset hooks intermediate the ends of each bar at the edge opposite to that at which the flange 30 is located, the lengths of the hooks being less than the depths of the grooves in the guide and less than the width of the flange

so that the free ends of the hooks will not contact with the back of the frame, the hooks constituting hangers for slotted cards 35 and rearwardly projecting members carried by each bar of greater lengths than the lengths of the rearwardly projecting hooks to maintain the rearwardly projecting hooks away from the back of the frame. 40

2. A card carrying bar for directory racks comprising a channel shaped member having flexible, flat portions, said bar being provided with hooks for receiving cards having 45 bight portions projecting from one side of said body portion and free ends projecting from the other side thereof, and flanges of greater width than the free ends of the hooks so that when the flanges are received in the directory rack, the free ends of the hooks 50 will be spaced away from the rack to permit the card to be placed upon the hooks and removed therefrom.

3. A card carrying bar for directory racks comprising a channel-shaped member 55 of flexible material, the top and bottom flanges of which are cut away at certain points in the length of the bar, the cut-away portion extending to the web of the channel so that the intermediate portion of 60 the channel may be flexed to introduce and remove the bar from the rack.

In testimony whereof I affix my signature.
JOSEPH R. DUMONT.
